UNITED STATES PATENT OFFICE.

CHARLES H. LANGILL, OF BOSTON, MASSACHUSETTS.

METHOD OF MAKING SHEAVES.

1,104,200.

Specification of Letters Patent.

Patented July 21, 1914.

Application filed September 22, 1913. Serial No. 791,251.

To all whom it may concern:

Be it known that I, CHARLES H. LANGILL, a citizen of the United States of America, and a resident of Boston, in the county of 5 Suffolk and State of Massachusetts, have invented certain new and useful Improvements in Methods of Making Sheaves, of which the following is a specification.

This invention relates to methods of casting sheaves and has for its object the production of sheaves with hardened steel tread surfaces cast therein.

The invention consists in a novel method of casting the sheaves which will be fully understood by reference to the description of the drawings and to the claims to be hereinafter given.

Of the drawings: Figure 1 represents a horizontal section of a mold or flask having positioned therein the tread portion of a pulley and the patterns used in casting said pulley. Fig. 2 represents a vertical section of the same, the cutting plane being on line 2—2 on Fig. 1, and Fig. 3 represents a similar section of the same inverted, with the wooden patterns removed ready for the casting metal to be poured therein.

Similar characters designate like parts throughout the several figures of the drawings:

In the drawings, 10, 11, and 12 are respectively the upper, central, and lower parts of a flask or mold. These parts are adapted to be positioned relative to one another when in use by means of the locking pins 13 and 14. When it is desired to cast a pulley the lower flask 12 is partially filled with sand 15 and the pattern 16 is then superimposed thereon, the most of the pattern extending 40 above the upper face of said part 12. With the pattern 16 properly positioned the annular tread portion 17 is positioned thereon within the annular ribs 18 formed upon said pattern 16. This tread portion 17 is preferably of hardened steel cast integral and is positioned in the central part 11 of the flask or mold. This central part 11 of the flask is then filled with sand and firmly packed 50 within the peripheral groove of said tread portion 17. Another pattern 19 is superimposed upon the tread portion 17 and the first mentioned pattern 16 as indicated in Fig. 2 of the drawings. This pattern 19 also has an annular rib 20 surrounding the edge 55 of the tread portion 17. The upper part of the flask is then positioned on the part 11 and

filled with sand in the usual manner. When the sand has set sufficiently and is in condition for casting the upper part 10 with the sand packed therein is separated from the central part 11 and the pattern 19 removed therefrom. The part 10 with one part of the molded sand therein is then replaced and secured to the central part 11 by means of the pins 13. The entire mold or flask is then inverted and the part 12 with the sand packed therein is separated from the central part 11 and the pattern 16 is removed. After the removal of the pattern 16 the part 12 with another part of the molded sand therein is replaced and secured to the central part 11 by means of the pins 14. This results in the cavity 21 being formed within the flask while the tread portion 17 is supported in proper position relative to this cavity 21 by means of the sand within the central part 11 of the flask. This causes the tread portion 17 to be utilized as one of the patterns, this particular pattern being left in the flask when the other patterns have been removed preparatory to casting the sheave. When the molten metal is poured into the cavity 21 a sheave will be formed with a hardened steel tread portion 17 cast therein and retained in position by means of 85 annular ribs cast on said sheave and surrounding the peripheral edges of said tread portion.

By this method of casting a sheave may be formed integral of suitable metal having an annular tread portion of harder metal cast therein in such a manner as to prevent its displacement. The advantages of a sheave thus constructed to be used for various purposes is obvious. The present 95 method of casting provides a simple means of manufacturing such sheaves in which the body portion may be of brass and the tread portion of hardened metal.

It is believed that the operation and many 100 advantages of this invention will be fully apparent from the foregoing description.

Having thus described my invention, I claim:

1. The method of casting sheaves consisting of positioning an annular steel tread portion in the central part of a flask by sand packed therein with patterns on either side thereof, said patterns having annular ribs adapted to fit over the edges of said tread 110 portion and being surrounded by sand, removing said patterns, and pouring metal into

the cavities formed by the removal of said patterns, thereby embedding the tread portion in the periphery of said pulley.

2. The method of casting sheaves consisting of positioning a pattern in an outer part of a flask by means of sand packed therein, positioning an annular metal tread portion on said pattern and in a central part of the flask by means of sand packed therein, positioning the other pattern in the other outer parts of said flask and partly upon said tread portion, packing sand around said last mentioned pattern, removing the upper part of the flask, removing the upper pattern, replacing said upper part of the flask, inverting the entire mold, removing the other pattern in the same manner and replacing the part of the flask from which the other pattern had been removed, and pouring metal into the cavities formed by the removal of said patterns.

3. The method of casting sheaves consist-

ing of positioning an annular metal tread portion in a central part of a flask by means of sand packed therein with patterns positioned on either side thereof by sand in the outer parts of said flask, said patterns being provided with annular ribs fitting over the edges of said tread portion, removing the upper part of the flask, removing the upper pattern, replacing said upper part of the flask, inverting the entire mold, removing the other pattern in the same manner, and replacing the part of the flask from which it was removed, and pouring metal into the cavities formed by the removal of said patterns.

Signed by me at 4 Post Office Sq., Boston, Mass., this 18th day of September, 1913.

CHARLES H. LANGILL.
